UNITED STATES PATENT OFFICE.

LE ROY E. JOLLS, OF DETROIT, MICHIGAN, ASSIGNOR TO PACKARD MOTOR CAR COMPANY, OF DETROIT, MICHIGAN, A CORPORATION OF MICHIGAN.

CUTTING TOOL.

1,403,555.

Specification of Letters Patent. Patented Jan. 17, 1922.

Application filed May 17, 1917. Serial No. 169,252.

To all whom it may concern:

Be it known that I, LE ROY E. JOLLS, a citizen of the United States, and resident of Detroit, Wayne County, State of Michigan, have invented certain new and useful Improvements in Cutting Tools, of which the following is a specification.

This invention relates to improvements in cutting tools and particularly to improvements in cylinder head doming tools.

The manufacture of cylinders for a hydro-carbon motor calls for the step of shaping the interior of the cylinder head. As usually made the cylinder head is somewhat irregular in outline and at one point at least overhangs the cylinder proper. In order to cut out or dome the overhanging portion a tool known in the trade as a doming tool is employed. One object of this invention is to provide a tool of this character which can be readily adjusted to cutting position without affecting the driving connections.

Another object of the invention is to provide a gearing mechanism made up of an internal gear and pinion which permits changing the relative positions of the gear and pinion carrying elements without disconnecting the driving connection.

A further object of the invention is to provide a doming tool having the head carrying shaft mounted in a sleeve eccentrically positioned in the tool.

Other objects of the invention will appear from the following description taken in connection with the drawings which form a part of this specification, and in which:

Fig. 1 is a sectional elevation of part of a cylinder of a hydrocarbon motor and a doming tool embodying one form of the invention;

Figs. 2 and 3 are transverse sections taken on the lines 2-2 and 3-3 respectively of Fig. 1 in the direction indicated by the arrows;

Fig. 4 is a sectional elevation of a doming tool embodying another form of the invention;

Fig. 5 is an end elevation taken from the right of Fig. 4; and

Fig. 6 is a sectional plan view of one form of cylinder in which such a tool may be employed.

In the drawings the reference character A is used to designate a motor cylinder of

the commonly called L type wherein the valves are all on one side. Cylinders of this form are usually domed only at the side opposite the valves, the extreme cutting depth being at B directly below the cylinder inlet opening C. As clearly shown in Fig. 6, the cutting depth shades off gradually from the deepest point to coincide with the circular walls at D. A doming tool must therefore be capable of making this varying cut.

One form of such a doming tool as set forth in Figs. 1, 2 and 3 has a frame or casting 10 composed of a central portion 11 and two projections or supporting members 12 and 13 extending from opposite sides of the central portion. The central portion 11 and projection 12 are in one part 14 of the frame while the projection 13 is in the other part 15. The two parts are threaded into each other at 16 and a set screw 17 is employed to hold the parts fixed. A recess 18 is provided in the central portion 11 and passages 19 and 20 leading from the recess 18 through the projections 12 and 13. The recess and passages are all tubular and differ in diameter, the recess 18 being the largest and the passage 19 the smallest. The center line of the recess 18 when extended forms the center line of the passage 19. The recess and passage may therefore be referred to as concentric. The center line of the recess 18 and passage 19 and the center line of the passage 20 are however parallel and the passage 20 may therefore be described as eccentric to the recess 18 and the passage 19.

Positioned in the passage 20 is a sleeve 21 having an eccentric passage 22 therethrough and flanges 23 at the inner end projecting into the recess 18. The sleeve while closely fitting in the passage may be rotated on its axis for a purpose to be described later; 90 bearings 24 are provided in the passages 19 and 22 through which extend shafts 25 and 26 respectively. The shaft 25 projects from the passage 19 and is provided at the outer end with notches 25' for engagement with the chuck of a drill press or other suitable machine (not shown).

At the inner end of the shaft 25 and, as here shown, integral therewith is an internal gear 27 located to turn in the recess 18. 105 The shaft 26 also projects from its passage 20 at either end and is provided at the outer end with a doming head 28 for shaping the

cylinder head and at the inner end with a pinion 29 which projects into the recess 18 and meshes with the internal gear 27. The shaft 25 as will be understood from the 5 above description is the driving element and the shaft 26 the driven element, power being transmitted from the driving to the driven element through the gear 27 and pinion 29.

Embedded in the bottom of the gear and 10 of the pinion are bearing plates 30. The plate in the gear has two races 31 and 32 and the plate in the pinion has the race 33 in which races work ball bearings 34 the balls being held in position by a retaining 15 ring 35. The plate 30 on the pinion has a center projection 36 over which the retaining ring 35 is slipped and positioned.

The rotation of the sleeve 21 referred to 20 above is carried out in the following manner. A slot 37 is cut through the wall of the central portion 11 and extends, as shown in Fig. 3, about one quarter way around. Through this slot passes a rod 38 threaded into a hole in the flange 23 of the sleeve 21.

25 The rod if extended would pass through the center of the sleeve and the latter will therefore be rotated on its axis as the former is moved in the slot 37. The amount of rotation permitted the sleeve 21 by the movement of rod 38 in slot 37 is so limited that the teeth of the pinion 29 will always be in mesh with the teeth of the gear 27 sufficiently to transmit the driving motion of the shaft 25 to the shaft 26.

30 Diametrically opposite the hole receiving the rod 38 is a second hole which has a locking function. Threaded into a hole in the central portion 11 is a cap 39 in which is mounted a pin 40. A projection 41 from 40 the pin extends through the cap and has secured thereto a handle 42. Coiled around the projection 41 within the cap is a spring 43 which bears against the rear of the pin and tends to force it into the hole in the 45 sleeve. When the sleeve is so anchored the shaft 26 is, as shown, in the position nearest the edge of the projection 13 so that the doming head projects beyond the side of the tool in its extreme cutting position.

50 A handle 44 for the tool is here shown as threaded into the central portion 11. Suitable oiling devices 45 are provided for lubricating the moving parts, the construction of these devices however, does not enter into this invention and they will not be described in detail.

55 A plate 46 is provided for properly positioning the doming tool in the cylinder. The plate as here shown has a hole substantially the size of the projection 13 and is slipped over it up to the central portion 11. A groove 47 in the projection and a set screw 48 in the plate permit relative rotary movement but prevent relative lateral movement. The tool is here shown as working

on a motor cylinder having an inclined base and the face of the plate is correspondingly inclined. Obviously, the face of the plate employed will be inclined according to the form of cylinder to be domed. The inclined portion 49 at its lower end provides a notch 50 the proper distance from the doming tool and into which the cylinder flange 51 will seat. Holding the cylinder in place is a bar 52 pivoted at the lower end 75 of the plate 46 and clamped upon the upper side of the flange 51 by the following means.

Pinned to the bar 52 by a key 53 is a bolt 54 which extends through an opening in the plate 46. Bolted to that plate is a plate 55 80 having a slot therein through which the bolt 54 can pass. A nut 56 is threaded on the end of the bolt 54 and when tightened against the plate will draw the bar against the cylinder flange. 85

The operation of the doming tool is believed to be obvious from a consideration of the drawings and specification but a short description thereof may be in order. The driving shaft is fitted into the chuck of a 90 drill press or other machine and the doming head set in rotation through the gear 27, pinion 29 and shaft 26. The anchoring pin 40 is now withdrawn and the sleeve 21 rotated by the handle 38 thus moving the doming head around into its inoperative position in which it does not overhang the projection or supporting member 13. The head being in this position the tool is now inserted in the cylinder and the cylinder is clamped in 95 the position shown in Fig. 1 by the bar 52 against the plate 46. The operator now moves the bar 38 slowly along the slot 37 at the same time causing the doming head to be adjusted laterally or to project further 100 out from the side of its supporting member 13. This will result in cutting a curve at the cylinder head the deepest being when the cutter is in the position shown in the drawing. The pin now slips into place and indicates that the deepest cut is now being 105 made. The operator now withdraws the pin and continues to move the bar 38 in the slot until it reaches the other end and the head is again in the inoperative position, i. e., 110 withdrawn from beyond the edge of the projection 13. The tool is now unclamped from the cylinder and withdrawn. It will be noticed that the gearing mechanism employed in this tool permits the uniform 115 operation of the doming head regardless of the position.

Figs. 4 and 5 show a somewhat simpler form of doming tool which is adapted to 120 perform the same function and in addition is constructed to be moved bodily during the doming operation. This doming tool comprises a frame or casing 60 having a tubular passage 61 eccentrically bored through it from end to end. Mounted in 125

the passage 61 is a sleeve 62 which also has in its turn a tubular passage 63 eccentrically bored. At either end of the passage is provided bearings 64 in which is mounted 5 a shaft 65 having fastened at the outer end a doming head 66 and at the inner end a bit 67 provided with notches 68. The bit end is placed in the chuck of a drill press or other suitable machine and the head 66 10 rotated.

The bit 67 is positioned by the pin or key 69 and the portion of the shaft between the bit and the sleeve is threaded for engagement by a nut 70, washers 71 being introduced 15 between the nut and the sleeve to hold the shaft against endwise movement and at the same time permit its rotation.

The frame 60 has a circular ridge or projection 72 and behind it is a collar 73 having 20 a rectangular outline. The collar is recessed to enclose the ridge 72 and has an inclined face which contacts with the cylinder A. Stops 74 are provided on the collar 73 which engage the outer edge of the cylinder flange 50 to insure the proper positioning of the tool in the cylinder.

Threaded on the frame 60 behind the collar 73 is a second collar 75 projecting from which is an arm or handle 76. The collar 30 75 carries on the face away from the collar 73 a circular projecting flange 77 threaded on its outer cylindrical surface to receive a cap 78 slipped over the sleeve 62 and having the interior of the projecting flange 35 correspondingly threaded to engage the flange 77. Threaded onto the sleeve 62 between the frame 60 and the cap 78 are nuts and washers 79. In the cap are provided set screws 80 which are adapted to contact 40 with the circular flange 77 and position the cap 78 with reference to the collar 75. The collar 75, cap 78 and nuts and washers 79 act to positively hold the sleeve in a predetermined endwise relation to the frame.

45 The washers however, permit relative rotary movement for the purpose to be disclosed hereafter. Pinned to that portion of the sleeve 62 projecting beyond the cap 78 is a handle 81 adapted to be oscillated 50 to turn the sleeve 62 and shaft 65 about the center line of the former. A securing device is provided to fasten the handles 76 and 81 together. This device comprises a band 82 fixed on the handle 76 by a set screw 83 55 on the band, which engages a groove 84 on the handle. Obviously the band may be shifted by loosening the set screw sliding it to the desired position and tightening the screw again. The handle 76 has an inclined

60 portion between the collar 75 and the groove 84 so that the lower part which carries the groove is adjacent and parallel to the handle 81. The band 82 has a circumference sufficient to enclose both handles 65 and the handle 81 is so much shorter than

the handle 76 that when the band is fixed in an upper position it will include both handles and when in a lower position is below the end of the handle 81. Thus it is possible either to hold the handle 81 in the 70 position shown in Fig. 4 wherein the doming head is in the extreme cutting position or to release it so that it can be oscillated independently of the handle 76 to shift the position of the head. 75

This form of doming tool is adapted to be operated similarly to the first embodiment described that is the tool is connected to the chuck of a drill press and the shaft carrying sleeve is rotated on its axis advancing and retracting the doming tool between its inoperative position and its extreme cutting position. Furthermore it will be noted that this form of tool is not clamped to the cylinder but is merely positioned thereon by the pins 74 which engage the cylinder flanges. Through this construction the tool as a unit can be rotated with the doming head at the extreme position to dome out to the same depth a larger 80 portion of the cylinder head than is possible with the first embodiment. 85

90 While two forms only of doming tools embodying the invention have been shown and described it will be obvious that other 95 forms may be made which will fall within the scope of the invention as set forth in the annexed claims.

Having thus described my invention, what I claim and desire to secure by Letters Patent is:— 100

1. A cylinder head doming tool comprising a frame having a tubular central portion and tubular projections at opposite sides from said central portion, bearing sleeves in each of said projections, a doming head carrying shaft eccentrically mounted in one of said bearing sleeves, a driving shaft concentrically mounted in the other of said bearing sleeves and means located in said 105 central portion for connecting said shafts. 110

2. A cylinder head doming tool comprising a frame, having a tubular central portion and tubular projections at opposite sides from said central portion, bearing sleeves in each of said projections, a doming head carrying shaft eccentrically mounted in one of said bearing sleeves, a driving shaft concentrically mounted in the other of said bearing sleeves and gearing mechanism 115 located in said central portion for connecting said shafts. 120

3. A cylinder head doming tool comprising a frame having a tubular central portion and tubular projections at opposite sides from said central portion, bearing sleeves in each of said projections, a doming head carrying shaft eccentrically mounted in one of said bearing sleeves, a driving shaft concentrically mounted in the other 125 130

- of said bearing sleeves and internal gear and pinion mechanism located in said central portion for connecting said shafts.
4. A power transmitting device comprising an elongated frame, having a central tubular recess and passages from said recess to the ends of the frame, one of said passages being concentric and the other eccentric with respect to said recess, a concentric bearing sleeve in said concentric passage and an eccentric bearing sleeve in said eccentric passage, a shaft mounted in each of said bearing sleeves and gearing located in said recess for connecting said shafts.
- 10 5. A power transmitting device comprising an elongated frame having a tubular recess at the center and tubular passages therefrom to the ends of said frame, one of said passages being eccentric with respect to said recess, bearing sleeves in said passages, a driving element mounted in the bearing sleeve in one of said passages, an internal gear in said recess secured to the end of said element, a driven element mounted in the bearing sleeve in said eccentric passage, a pinion at the end of said driven element meshing with said internal gear and means for shifting the bearing sleeve in said eccentric passage to change the position of said driven element in said eccentric passage and relatively to said driving element.
- 15 6. The combination with a piece to be operated upon, of a frame adapted to be retained against movement relative to said piece, a tool shaft mounted for lateral adjustment in said frame, a driving shaft, and gearing between said shafts including an internal gear on the driving shaft.
- 20 7. The combination with a piece to be operated upon, of a casing adapted to be retained against movement relative to said piece, a tool shaft mounted for lateral adjustment in said casing, a driving shaft, and gearing in said casing between said shafts including an internal gear on the driving shaft.
- 25 8. The combination with a piece to be operated upon, of a casing adapted to be retained against movement relative to said piece, a tool shaft mounted for lateral adjustment in said casing, a driving shaft, and gearing between said shafts including an internal gear on one of said shafts.
9. A tool comprising an elongated casing, a driving shaft supported in a bearing at one end of the casing and having a gear inside the casing, a driven shaft for the cutting head having a gear in the casing in mesh with the first gear, and means for laterally adjusting the driven shaft comprising an oscillating sleeve in which the driven shaft is eccentrically mounted.
- 10 10. A tool comprising an elongated casing, a driving shaft supported in a bearing at one end of the casing and having a gear inside the casing, a driven shaft for the cutting head having a gear in the casing in mesh with the first gear, and means for laterally adjusting the driven shaft comprising an oscillating sleeve in which the driven shaft is eccentrically mounted, the axis of said sleeve being nearly coaxial with the driving shaft so that the gears will remain in running mesh as the sleeve is oscillated.
- 15 11. A cylinder head doming tool comprising a casing part adapted to be secured to the cylinder to be operated upon, a doming tool shaft mounted for lateral adjustment therein, a pinion on said shaft, and an internal gear mounted to rotate in said casing part and remain in running mesh with said pinion in the various adjusted positions of said tool shaft.
- 20 12. A cylinder head doming tool comprising a guiding part adapted to be inserted in the cylinder, a bearing sleeve in said guiding part having means for oscillating it in the guiding part, an eccentric bearing in said sleeve, a doming head shaft mounted in said bearing, and means for driving said shaft.
- 25 13. A cylinder head doming tool comprising a guiding part adapted to be inserted in the cylinder, an eccentrically mounted bearing sleeve in said guiding part having means for oscillating it in the guiding part, an eccentrically mounted shaft in said sleeve, and means for driving said shaft.
- 30 14. A tool comprising a guiding part of external cylindrical form, a bearing sleeve mounted in said guiding part eccentrically to the periphery of the latter, means for oscillating said sleeve, a tool shaft mounted eccentrically in said sleeve, and means for driving said shaft.
- 35 In testimony whereof I affix my signature.
- LE ROY E. JOLLS.
